INTERNAL ELECTRICAL FEELER FOR SHUTTLES

Application filed September 26, 1930. Serial No. 484,598.

This invention relates to improvements in weft detecting features of spindle shuttles and it is the general object of the invention to provide a penetrating feeler which shall 5 act from a point within a wound mass of weft and tend to move outwardly through the latter to give indication of weft exhaustion.

The usual spindle shuttle is provided with a transverse pivot on which is mounted a 10 spindle having portions normally tending to separate to grip the interior walls of a weft carrier, such as a cop. In constructions which I have heretofore proposed a lever is mounted for pivotal movement in the slot between 15 the resilient parts of the spindle and moves through a detecting slot in the weft carrier at the time of weft exhaustion so as to close an electric circuit or otherwise give indication of weft exhaustion. It is an important 20 object of my present invention to provide the detecting element with a part capable of penetrating a few coils of weft extending across the detecting slot so that the indicating movement of said element may take place 25 prior to the complete uncovering of the slot in the cop. In this way it is unnecessary to wind a bunch of reserve weft on the cop.

In the usual form of weft detector, either 30 on the lay or a stationary support, the detector engages the weft when the latter is not unwinding. In the present instance, however, the detector will have its tooth or teeth projecting through the weft when the latter 35 is unwinding, and it is an important object of my invention to provide a detecting surface or element which will permit the ready uncoiling of the weft without interfering with this operation at such times as exhaustion of weft approaches. I may use either a 40 flexible tooth which will yield to avoid yarn breakage, or a rigid tooth formed with a cam surface to guide the weft over the tooth without breaking.

45 With these and other objects in view which will appear as the description proceeds, my invention resides in the combination and arrangement of parts hereinafter described and set forth in the claims.

50 In the accompanying drawing, wherein

two forms of detecting teeth are conveniently set forth,

Fig. 1 is a longitudinal vertical section through a shuttle made according to the preferred form of my present invention,

55 Fig. 2 is a top plan view of the shuttle shown in Fig. 1,

Fig. 3 is a view similar to a portion of Fig. 1 but showing the detecting end of the lever penetrating a small layer of weft overlying the detector slot in the weft cop or weft carrier,

60 Fig. 4 shows a side elevation of a detector lever having the modified yarn penetrating element, on an enlarged scale, and

65 Fig. 5 is a detail vertical section on line 5-5 of Fig. 4.

Referring to the drawing, the shuttle S is provided with a transverse pin 10 on which is pivotally mounted a spindle 11 formed of 70 two parts 12 and 13 between which lies a slot 14. One wall of the shuttle is provided with a pair of contact plates 15 and 16 which contact respectively with brushes 17 and 18 in circuit with electromagnetic devices not 75 shown capable of bringing about a change in the operation of the loom when said plates are connected electrically by proper conditions existing within the shuttle. The pin 10 is connected electrically to the plate 15, 80 while the plate 16 is electrically connected by means of a wire 19 to a spring 20 on the lower side of the shuttle.

85 A weft detector lever 21 is mounted for limited free pivotal movement about the pin 10 in the slot 14 and has a depending arm 22 to engage the spring 20. Normally the arm is out of contact with the spring as shown in Fig. 1, thereby keeping the plates 15 and 16 out of electrical contact with each other.

90 The detecting lever in its preferred form has a horizontally extending portion in the spindle slot projecting away from the pin 10 and provided with an upwardly projecting relatively small finger or tooth 23 which is 95 positioned to move through a slot 24 in the cop 25 on which the wound mass of weft is carried. More than one tooth may be used if desired. A light compression spring 26 located between an arm 27 on the detector 100

lever and a spindle positioning flat spring 28 tends normally to move the tooth into the weft wound over the slot in the cop.

When sufficient weft is present the yarn lying across the slot 24 will hold the lever 21 in relatively low position with the arm 22 out of contact with the lower spring 20. When sufficient yarn has been drawn off the cop, however, so that the teeth 23 may penetrate the remaining few coils of yarn the lever will move upwardly from the position shown in Fig. 1 to that shown in Fig. 3 by action of the spring 26. This movement of the lever will bring about electric contact between the spring 20 and the arm 22, thereby electrically connecting plates 15 and 16 and completing the previously mentioned external circuit. A change in the operation of the loom will thereupon result, this change effecting either loom stoppage or exchange of shuttles.

When the detector lever gives indication of weft exhaustion the tooth or teeth which penetrate the weft will project above the yarn during the flight or flights of the shuttle intervening between indication and a change in loom operation. In order that the detector may not interfere with the unwinding of the weft I make the toothed part with smooth surfaces 29 which are inclined toward the cop butt and axis of the spindle. This avoids an abrupt shoulder on the bunch side of the tooth and permits free and easy unwinding of the yarn without danger of breakage.

In the modified form of detector the arm 40 has the end thereof folded on itself at 41 to grip several bristles 42 which are positioned to project through the slot in the weft carrier. Indication is effected in substantially the same manner as in the preferred form. The bristles are flexible and bent to avoid breaking the last few coils of weft as they unwind after indication of weft exhaustion is given.

Other parts shown herein but not specifically described may be substantially the same as those set forth more particularly in my co-pending application Ser. No. 484,596.

From the foregoing it will be seen that I have provided a simple means for providing an internally operating detector lever having penetrating teeth which tend to move outwardly through a slot in the weft carrier to pierce the last few coils of weft remaining on the weft carrier, a detector of this type permitting the use of a bobbin or other form of carrier which has not had a bunch of reserve weft wound thereon. The pressure of the spring tending to move the teeth toward the arm is very light so as not to cause wear of the yarn but is sufficient to cause penetration when the latter is desired. Also, the penetrating teeth are made so as not to interfere with the unwinding of the coils of weft after indication of weft exhaustion is given.

Having thus described my invention it will be seen that changes and modifications may be made therein by those skilled in the art without departing from the spirit and scope of the invention and I do not wish to be limited to the details herein disclosed, but what I claim is:

1. In a shuttle having a mass of weft therein, a detector member located within the mass and having flexible elements tending to project through the last few coils of weft to effect indication of weft exhaustion, the elements capable of yielding to permit unhindered uncoiling of the last weft coils.

2. In a shuttle having a mass of weft therein, a detector member located within the mass and having flexible elements tending to project through the last few coils of weft to effect indication of weft exhaustion, the elements being formed of bristles capable of yielding under action of the weft to avoid breakage of the latter as the last coils of weft unwind.

In testimony whereof I have hereunto affixed my signature.

RICHARD GREENLEAF TURNER.
